UNITED STATES PATENT OFFICE.

JAMES EARL GREEN, OF MINNEAPOLIS, MINNESOTA, ASSIGNOR TO MCCLINTOCK-LOOMIS COMPANY, A CORPORATION OF MINNESOTA.

DESIGN FOR A CHIME-CLOCK CASE.

40,234.

Specification for Design.

Patented Aug. 24, 1909.

Application filed June 21, 1909. Serial No. 503,555. Term of patent 7 years.

To all whom it may concern:

Be it known that I, JAMES EARL GREEN, a citizen of the United States, residing at Minneapolis, in the county of Hennepin, State of Minnesota, have invented a new, original, and ornamental Design for a Chime-Clock Case, of which the following is a specification, reference being had to the accompanying drawing, forming a part thereof.

The figure is a perspective view of a chime clock case, showing a new design.

I claim:

The ornamental design for a chime clock case as shown.

JAMES EARL GREEN.

In presence of—

RICHARD PAUL,
J. A. BYINGTON.
